(57) **CLAIM**

We claim the ornamental design for a swing training weight, as shown and described.

DESCRIPTION

FIG. 1 is a perspective view of a swing training weight, showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a cross-sectional view thereof, taken generally along lines 8-8 of FIG. 6.

The broken lines showing a sporting bat in FIG. 1 depict environmental matter and form no part of the claimed design.
